UNITED STATES PATENT OFFICE.

ISAAC SHIMWELL McDougall, of Irk Vale, Chadderton, near Manchester, County of Lancaster, England.

PRODUCTION OF SULPHUROUS ACID.

SPECIFICATION forming part of Letters Patent No. 311,595, dated February 3, 1885.

Application filed September 22, 1883. (No model.) Patented in England March 13, 1883, No. 1,349.

To all whom it may concern:

Be it known that I, ISAAC SHIMWELL McDougall, a subject of the Queen of Great Britain, and residing at Irk Vale, Chadderton, near Manchester, in the county of Lancaster, England, have invented certain improvements in the production of sulphurous acid or salts or solutions containing sulphurous acid, and in the mode of applying the same to the treatment of wood pulp and other purposes, (for which I have obtained a patent in Great Britain No. 1,349, dated March 13, 1883,) of which the following specification is a full description.

15 Solutions of sulphurous acid and sulphites and bisulphites of alkaline earths have been produced to be employed in the production of pulp by burning sulphur compounds with the oxygen of the air and conducting the sulphurous-acid gas produced upward through a tower or vertical column containing suitable material to diffuse the gas when it is brought into contact with water or alkaline solutions passing down over the diffusing material.

25 This means of production is inconvenient, as in such towers it is difficult to condense the whole of the gas or to produce solutions of regular strength, and considerable nuisance is sometimes caused by the escape of gases.

30 By means of my improvements I produce sulphurous acid or solutions containing sulphurous acid or sulphite or bisulphite or other solutions or other salts without employing condensing towers or columns. I accomplish this by burning sulphur or pyrites or spent oxide of iron or other suitable sulphur compounds in strong inclosed vessels, into which, after igniting the sulphur or its compounds, I force air by any suitable mechanical means, such as an air-pump or fan of sufficient power to drive the sulphurous-acid gas through suitable pipes or connections into a vessel or series of vessels containing water or solutions of alkalies or alkaline earths, with which it is desired the gas shall be brought into contact for the purpose of obtaining products containing sulphurous acid; or, when preferable, I force the air or gas forward by suction by suitably placing the air-pump or fan for that purpose.

45 In all cases I maintain a low temperature in

the retort sufficient to prevent the volatilization of the sulphur, and this I prefer to do by surrounding with water the vessel or vessels in which the sulphur is burned and the pipes or connections carrying the sulphurous gas, for 55 the purpose of reducing the temperature of the same. Complete control is maintained over the sulphurous-acid gas, the gas being conveyed to a distance down below the surface of the liquor or solutions or materials in 60 the vessel or series of vessels, the pressure forcing the same through the contents of the said vessel or vessels. The gas, or solutions of it or sulphite or bisulphite solutions or other salts or mixtures of them, may be prepared of any strength and in any quantities desired for employment in the treatment of 65 pulp, or for other purposes.

The accompanying drawings illustrate what are regarded as the best means for successfully carrying out the process, Figures 1 and 1^a taken together showing in elevation a complete apparatus for the purpose.

A represents a blowing-engine to blow air with sufficient force through suitable vessels, 75 B, containing sulphur or sulphur compounds. As the air comes in contact with the sulphur under considerable pressure (after the sulphur has become ignited by applying a red-hot iron internally, or by other suitable means within 80 the vessel) no external heat is needed, but the vessel is required to be immersed in water to prevent the heat becoming too great, or sublimation would take place, which would stop and spoil the working of the process. 85 The gases then pass through pipes cased with suitable jackets, B', containing water to cool the gases as they are conveyed forward. The gases are then conveyed by the pipes C into suitable vats or vessels, E, in which are fixed 90 vertical agitators H, to keep the liquor or sediment in motion to be more readily acted upon by the passing gases. The vats are connected together at the bottom by passages with stop-taps S, which are always kept closed while the 95 process of blowing the gases is in operation. A pipe with a tap, T, is a means of inlet for the solutions required to be acted upon in the vats. By the regulation of the taps of the 100 passages S and T the liquor can be regulated,

as desired, in the vats when the process of blowing is stopped, as desired. Before the process of blowing is commenced the vats are filled considerably above the opening of the 5 inlet-pipes C, so that the gases have to pass through this head of pressure of solution. On the last vessel is an outlet-pipe, D, to carry away the waste gases. Upon each vat or vessel is placed a gage-glass, G, with suitable 10 taps to show the height of the solutions in the vats, and from which samples can be readily taken to show when the solutions are saturated. When the solution in vat No. 1 becomes sufficiently saturated, the blowing is discontinued 15 and the contents of vat No. 1 emptied to be used for the purpose required. After No. 1 vat is emptied the taps are opened and the whole of the vats filled to a convenient height, the blowing being continued until the first vat 20 is again saturated, and so the process being continued as desired. The gases pass from vat I to vat II, and then to vat III, and through as many other vats in like manner as may be found sufficient to absorb the sulphurous-acid 25 gases, and at the last vat the waste gases pass through the exit-pipe D to a chimney or other means of exit.

Having now explained my said invention and the manner of carrying the same into effect, I would observe, in conclusion, that heretofore a process of making sulphurous-acid liquors has been devised in which the sulphur or pyrites is burned by means of air under pressure in a close retort provided with a water-jacket, and the sulphurous acid produced is afterward and while still under pressure delivered into the bottom of a tower filled with gravel or its equivalent that is continually kept wet with the absorbing liquid; but this 30 process is essentially different from my invention, in which the mixed sulphurous gases

from the combustion of the sulphur or pyrites are not absorbed in a tower by a liquid trickling over gravel, but are delivered below the surface of a body of absorbing liquid in one or 45 a series of vessels, wherein the sulphurous acid is dissolved, the solution being assisted by agitation of the liquid. In my invention the pressure in the retort, which is caused by the blower, and is consequently independent of 50 the reaction for producing the sulphurous acid, is sufficient to overcome the back-pressure of the liquid through which the mixed sulphurous gases from the retort have to pass. In the old process above referred to the pressure 55 in the absorbing vessels is maintained by cocks and valves, and the sulphurous gases do not pass through a large body of liquid, but meet the thin streams of liquid filtering over the gravel in the tower. 60

I claim—

The method of producing sulphurous acid by forcing air under pressure into a close vessel or retort containing ignited sulphur or sulphur-bearing material, and maintaining a low 65 temperature in said vessel or retort by surrounding the same with a cooling medium—such as water—and conducting the sulphurous gases from said retort into and below the surface of an absorbing liquid in one vessel or a 70 series, where it is allowed to escape, substantially as described.

In testimony whereof I have signed my name to this specification in the presence of two subscribing witnesses.

ISAAC SHIMWELL McDougall.
